193,835

UTILITY MAT OR SIMILAR ARTICLE

Maurice H. Kraines, Los Angeles, and Robert L. Unkrich,
Long Beach, Calif.; said Unkrich assignor to said
Kraines

Filed Dec. 26, 1961, Ser. No. 68,057

Term of patent 14 years

(Cl. D9—6)

FIG. 1 is a front perspective view of a utility mat or similar article embodying our new design;

We claim:

The ornamental design for a utility mat or similar article, substantially as shown.
